(57) **CLAIM**

The ornamental design for an oil sight glass, as shown and described.

DESCRIPTION

FIG. 1 is a front perspective view of an oil sight glass, showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a bottom perspective view thereof;

FIG. 9 is an exploded front perspective view thereof;

FIG. 10 is a part view of the portion '10' in FIG. 9;

FIG. 11 is a part view of the portion '11' in FIG. 9; and,

FIG. 12 is another front view thereof in an environment of use.

Oblique line shading in the figures depict a transparent surface and forms no part of the claimed design.

The dash broken lines in FIG. 9 show the locations from which the part views FIGS. 10 and 11 are taken and form no part of the claimed design.

The dash-dash broken lines in FIG. 12 depict environmental subject matter and form no part of the claimed design.
